METHOD OF AND MACHINE FOR
ATTACHING SOLESCutler D. Knowlton, Rockport, Mass., assignor to
United Shoe Machinery Corporation, Flemington, N. J., a corporation of New Jersey

Application April 13, 1944, Serial No. 530,849

11 Claims. (Cl. 12—33)

This invention relates to a method of and a machine for attaching soles to shoes and is in particular concerned with the activation of thermoplastic cement previously applied to a shoe bottom and a sole as well as the attachment of that sole to the shoe by the application of pressure to the sole after the cement on the shoe bottom and the sole has been activated and the sole has been laid upon the shoe bottom.

It is one of the objects of the invention to insure a uniform and simultaneous activation of thermoplastic cement on a shoe bottom and a sole, and a quick attachment of the sole to the shoe after the cement has been activated.

To this end, the invention in its method aspect is characterized by locating a shoe bottom and a sole, to the attaching faces of which a thermoplastic cement has been applied, at equal distances from a heating device from which parallel heat rays are being emitted so that the rays are substantially normal to the attaching faces of the shoe bottom and the sole. This insures a uniform activation of the thermoplastic cement on the attaching faces of both the shoe bottom and the sole. After the cement activation, the sole is immediately laid upon the shoe bottom and attached thereto by pressure.

For the purpose of cement activation both the shoe and the sole preferably are so placed with relation to the heating device that their attaching faces are located with at least their greater portions substantially in the same plane to which the heat rays are normal.

The invention also provides a machine adapted for use in the practice of the above-mentioned method, and in accordance with another feature of the invention therefore, the illustrated machine is provided with shoe and sole supporting means which is spaced from a heating device emitting parallel heat rays and is so arranged with relation to the heating device that the heat rays are substantially normal to the attaching faces of both the shoe and the sole. In addition to this, the machine is provided with mechanism for quickly pressing together the shoe and the sole after the latter has been laid upon the shoe bottom.

Moreover, the illustrated machine in accordance with another feature of the invention is provided with a support for both the heating device and the pressing mechanism, the support being movable so as to locate the heating device and the pressing mechanism alternately in register with the shoe supporting means. When the heating device is in register with the shoe sup-

porting means, thermoplastic cement previously applied to the attaching faces of the shoe bottom and of the sole is activated. Movement of the support thereafter quickly brings the pressing mechanism into register with the shoe support so that without undue loss of time pressure may be applied to the sole which in the meantime has been laid upon the shoe bottom.

These and other features of the invention will now be described in detail with reference to the accompanying drawings and will be pointed out in the appended claims.

In the drawings:

Fig. 1 is a side elevation, partly in section, of a cement activating and sole attaching machine embodying the present invention;

Fig. 2 is a plan of part of the machine illustrated in Fig. 1; and

Fig. 3 is a front elevation of the pressing mechanism with certain parts broken away.

The illustrated machine serves the purpose of activating thermoplastic cement previously applied to a shoe bottom and a sole to be attached thereto, as well as of attaching the sole to the shoe bottom immediately after the activation of the cement, the attachment being effected by the application of pressure to the sole after the latter has been laid upon the shoe bottom. While the illustrated machine is primarily intended for use in shoe repair shops, it is by no means limited in its utility to shoe repair work, but can be used advantageously also in the manufacture of cement shoes.

After the application of a suitable thermoplastic cement to the attaching faces of both the shoe and the sole, the shoe and the sole are so located at equal distances from a heating device emitting parallel heat rays that the rays meet the said attaching faces substantially at right angles thereto. By this arrangement a maximum efficiency of the heating device is insured, reducing both time and cost of operation, and furthermore, the activation of the cement on the attaching faces of both the shoe and the sole is carried out uniformly so that when the sole is laid upon the shoe bottom the cement on both attaching faces is substantially in the same condition of activation.

The illustrated machine has a base 10 (Fig. 1) which is adapted to rest on a table or work bench and is provided with a boss 12 in which is secured a hollow externally threaded column or screw 14. Surrounding the column 14 and engaging the boss 12 is a clamping collar 16 upon which rests a heavy spring 18 surrounding the column 14.

The upper end of the spring 18 supports a collar 20 which is held against rotation and on which is mounted for rotation about the axis of the column 14 a two armed support 21, the arms 22, 23 of which extend in opposite directions. The arm 22 supports a heating device H which serves to activate the thermoplastic cement upon the attaching faces of the shoe and the sole, and the arm 23 serves to support a pressing mechanism P by means of which pressure is applied to the sole and the shoe bottom so as to attach the sole to the shoe. The support 21 is adjustable heightwise of the column 14 and to this end there is provided a hand wheel 26 the hub 24 of which rests on a collar 25 on top of the support 21 and has a tapped bore in threaded engagement with the screw threads of the column 14. The collar 25 is held against rotation but is movable heightwise with the support 21. Rotation of the hand wheel 26 in one direction causes downward movement of the support 21 against the pressure of the spring 18, and rotation of the hand wheel 26 in the opposite direction causes upward movement of the support 21 as a result of the expansion of the spring 18. This serves to adjust the heating device H with relation to the attaching face of a shoe S supported in the machine, as well as to adjust the pressing mechanism P with relation to the attaching face of the supported shoe. Thus the intensity and duration of the activation of the cement may be regulated, and moreover, the distance of travel necessary for the pressing mechanism to contact the sole laid upon the shoe bottom so as to apply pressure thereto may be adjusted to be as small as possible thus saving time.

The shoe S when presented to the machine comprises an upper and an insole (not shown) which have been worked into lasted relation on a last L and which are ready for the attachment of an outsole O (Fig. 2) thereto by a thermoplastic cement previously applied to the attaching faces of the shoe and the outsole.

In order to present the attaching face of the shoe in proper relation to the heating device as well as the pressing mechanism and to sustain the shoe against the sole-attaching pressure, the last with the shoe supported thereon, is mounted on a support or jack. Referring to Fig. 1 it will be noted that the base 10 is provided with a bracket 30 having two upstanding ears 32 in which is supported a horizontal pin 34. Mounted for pivotal movement about the pin 34 is a shoe and last supporting jack 36 which may be tilted into different angular positions and which is held in a selected angular position by suitable means (not shown). The jack 36 is substantially a two armed member having a downwardly extending projection which is mounted on the pin 34. One arm of the jack 36 carries an upwardly extending pin 38 which is received in the pin hole or thimble of the last when the latter is presented to the jack. The other arm of the jack carries a toe rest 40 supporting the toe end of the lasted shoe S. The toe rest 40 is adjustable along a slot 42 provided in the jack 36 and is held in adjusted position by a clamping screw (not shown). The adjustment of the jack about the pin 34 is made to locate the attaching face of the shoe or at least the greater portion thereof in a substantially horizontal plane. The adjustment of the toe rest 40 along the slot 42 is made to accommodate shoes of different sizes.

The heating device H is carried by a bracket 50 (Fig. 1) which is secured by bolts 52 to the

arm 22 of the support 21. The heater 54 proper is of the sun-bowl type and comprises a heating unit 56 and a parabolic reflector 58. It is well known that in heaters of this type the heating unit is so located with relation to the reflecting surface of the reflector 58 that the heat rays are emitted from the heater in a substantially parallel relation. As illustrated in Fig. 1 the heater is so arranged that the parallel heat rays are directed downward.

For the purpose of presenting the sole O coated with a thermoplastic cement to the heater 54 so as to activate the cement, there is provided a shelf 60 (Figs. 1 and 2). The shelf 60 is beneath substantially one half of the heater 54 when the heater is in register with the jack, and is spaced therefrom a predetermined adjustable distance. The shelf 60 is supported by a rod 62, the upper end of which is in threaded engagement with a boss 64 provided on the collar 20.

The aforementioned pressing mechanism P includes a press pad 70 of a type commonly used in cement sole attaching machines which is adapted to engage the sole O after the latter has been placed upon the bottom of the shoe S supported on the jack 36. The pad 70 is mounted and retained in a casing 72 which is arranged in the machine for heightwise movement toward and from the supported shoe S. As illustrated in Fig. 3 the casing 72 is provided on its top face with a boss 74 in which is secured by means of a tapered pin (Fig. 3) the lower end of a plunger 76. The plunger 76 is vertically movable in a bore 78 provided in the arm 23 of the support 21 and has a close fit in the lower portion of the bore 78, which portion is of reduced diameter. The upper portion of the plunger 76 is reduced in diameter and forms a stem 80 which is surrounded by a spring 82 the lower end of which is seated on a shoulder of the plunger 76 and the upper end of which engages a flanged sleeve 84 surrounding the upper end of the stem 80. Downward movement of the plunger 76 is effected by downward movement of the sleeve 84 through the agency of the spring 82, the spring yielding after the pad 70 has engaged the sole O on the bottom of the shoe S upon continued downward movement of the sleeve 84. The upper end of the sleeve 84 is normally held by the spring 82 against a nut 88 threaded upon the upper end of the stem 80.

To lower the sleeve 84 so as to move the pad 70 into pressing engagement with the sole O on the bottom of the shoe S, the sleeve 84 is surrounded by a rectangular block 90 secured to the sleeve 84 by a binding screw 92 (Fig. 1) so that both move as a unit. Downward movement is imparted to the block 90 by a double toggle. Each toggle has a lower link 94 (Fig. 3) pivotally secured by a fulcrum stud 96 to one end face of the block 90. The lower link 94 of each toggle is pivotally connected to an upper toggle link 100 by a center pin 98. The two upper toggle links 100 are integral with the forked end 102 of a hand lever 104. The hand lever 104 is rotatable about a horizontal stud 110 (Figs. 1 and 3), the opposite ends of which are secured by nuts 112 in two spaced uprights 114. The lower ends of both uprights 114 are secured to the opposite side faces of the arm 23 by screws 116.

As indicated in Fig. 1, in the inoperative position of the machine parts the sleeve 84 is maintained in its uppermost position determined by the nut 88, the double toggle 94, 100 is in its broken position, the hand lever 104 extends up-

wardly in an inclined direction, and the pad 70 is elevated above the tread face of the sole O previously laid upon the attaching face of the shoe S. Downward movement of the hand lever 104 causes the double toggle 94, 100 to be straightened thereby moving the sleeve 84 downward, which through the medium of the spring 82 depresses the plunger 76 and the pad 70 carried thereby so that the pad is caused to exert attaching pressure upon the tread face of the sole. In its straightened position the double toggle acts as a lock to hold the pad 70 in its pressure applying position.

The pad 70 after having remained in pressure applying position for a sufficient length of time is unlocked by breaking the double toggle 94, 100, this being done by an upward movement of the hand lever 104. The pad 70 and the machine parts connected therewith are then elevated into their inoperative positions. For this purpose the boss 74 of the pad casing 72 has secured in it by a tapered pin (Fig. 3) a rod 120, a portion of which is guided in a vertical bore 122 provided in a forward projection 123 of the arm 23. The upper portion of the rod 120 extending above the projection 123 is surrounded by a spring 124, the lower end of which is seated against the top face of the projection 123, and the upper end of which engages nuts 126 threaded upon the upper end of the rod 120. Upon depression of the pad 70 the spring 124 is compressed and consequently upon unlocking the pad 70 the latter is elevated by the spring 124.

As previously stated the support 21 is movable about the axis of the column 14. The rotation or preferably reciprocation of the support 21 takes place between two predetermined operative positions. In one of these positions the heater 54 is located above the bottom of the shoe S and the sole O supported in the machine. The arrangement is such that the attaching face of the forepart of the shoe bottom and the attaching face of the sole O resting bottom up on the shelf 60, are located substantially in the same plane and thus are located at equal distances from the heater. Moreover the arrangement is such that the parallel heat rays emitted from the heater 54 meet the attaching faces of both the shoe and the sole at right angles. As illustrated in the plan view of Fig. 2, in the operative position of the heater over the supported shoe, substantially one half of the heater serves to activate the cement on the attaching face of the shoe S, and the other half of the heater serves to activate the cement on the attaching face of the sole O on the shelf 60, the sole and the shoe in this position being located in side by side relation. After the activation of the cement on the shoe bottom and the sole, the support 21 is rotated about 180° so as to move the heating device H into its inoperative position and simultaneously to move the pressing mechanism P into its operative position over the supported shoe upon which, in the meantime, the sole with the activated cement thereon has been laid. Downward movement of the handle 104 quickly applies attaching pressure to the tread face of the sole O by the pad 70, the pad being held in pressure applying position by the extended double toggle 94, 100.

The support 21 is accurately located in either of its above mentioned two operative positions in which either the pressing mechanism P or the heating device H is in register with the supported shoe S by the following arrangement: The column 14 has a vertical keyway 130 (Fig. 1) pro-

vided therein which is engaged by a key 132 carried by the collar 20 thus preventing a rotary motion of the collar while permitting it to rise and fall with the support 21 upon heightwise adjustment thereof. The collar has at opposite sides thereof two abutments one being the boss 64 and the other a projection 136 (Fig. 2) with which cooperates an abutment pin 138 provided on the support 21. The abutments 64 and 136 are so located circumferentially of the collar that after a 180° rotation of the support 21, the abutment pin 138 engages one or the other of the two abutments thus accurately locating either the pressing mechanism P or the heating device H in their respective operative positions.

The length of travel necessary for the pad 70 to move from its inoperative position to apply pressure to the sole is adjustable to a minimum by the heightwise adjustment of the support 21 with relation to the column 14, this adjustment being effected by the rotation of the hand wheel 26.

After the sole O has become attached to the shoe S, the pad 70 is unlocked and moved into its inoperative elevated position as described. The shoe having its sole attached thereto is then removed from the machine and a new shoe to be soled is mounted on the jack. By a rotation of the support 21, the heating device H is then again located over the shoe and a new outsole is placed on the shelf whereupon the sole attaching cycle may be repeated. It will be seen that the heating device H and the pressing mechanism P by a simple rotation or reciprocation of their common support 21, are alternately located in their operative positions in register with the shoe on its support.

It is understood that the heating device H is supplied in a suitable manner with electric current from a suitable supply.

Having described my invention, what I claim as new and desire to secure by Letters Patent of the United States is:

1. A method of attaching soles to shoes which comprises providing a shoe and a sole having thermoplastic cement on their attaching faces, locating said attaching faces with at least their greater portions substantially in the same plane, so locating a heating device emitting parallel heat rays that the heat rays are normal to said plane to activate the cement on said attaching faces, locating the sole upon the shoe while the cement is in activated condition, and pressing the shoe and the sole together.

2. A method of attaching soles to shoes which comprises providing a shoe and a sole having thermoplastic cement on their attaching faces, locating said attaching faces with at least their greater portions at equal distances from a heating device emitting parallel heat rays, with said attaching faces so facing the heating device that the rays are normal to them to activate the cement thereon, locating the sole upon the shoe while the cement is in activated condition, and pressing the shoe and the sole together.

3. A cement sole attaching machine comprising means for supporting a shoe and a sole having thermoplastic cement on their attaching faces with said attaching faces disposed at least with their greater portions in substantially the same plane, heating means spaced from that plane and arranged to emit parallel heat rays normal to said plane to activate the cement, and means for pressing the shoe and the sole together.

4. A machine for simultaneously activating ce-

ment on the attaching faces of shoes and soles, having in combination means for separately supporting a shoe and a sole having thermoplastic cement on their attaching faces, and a heating device spaced an equal distance from the attaching faces of the supported shoe and sole and emitting parallel heat rays normal to said attaching faces so as to activate the cement.

5. A cement sole attaching machine comprising means for supporting a shoe having thermoplastic cement on its attaching face, means for supporting a sole having thermoplastic cement on its attaching face, heating means arranged to activate the cement on both the shoe and the sole, means for pressing the shoe and the sole together, and a common movable support for said heating means and pressing means adapted to locate said heating means and pressing means alternately in register with said shoe supporting means.

6. A cement sole attaching machine comprising separate means for supporting a shoe and a sole having thermoplastic cement on their attaching faces with said attaching faces disposed at least with their greater portions in substantially the same plane, heating means spaced from said plane and arranged to emit parallel heat rays normal to said plane to activate the cement, means for pressing the shoe and the sole together, and a common movable support for the heating means and pressing means adapted to locate said heating means and pressing means alternately in register with said shoe supporting means.

7. A cement sole attaching machine comprising means for supporting a shoe having thermoplastic cement on its attaching face, means for supporting a sole having thermoplastic cement on its attaching face, heating means arranged to activate the cement on both the shoe and the sole, means for pressing the shoe and the sole together, a common movable support for said heating means and pressing means adapted to locate said heating means and pressing means alternately in register with said shoe supporting means, and means for adjusting said common support heightwise of the machine to space the heating means and pressing means at predetermined distances from the supported shoe.

8. A cement sole attaching machine comprising means for supporting a shoe having thermoplastic cement on its attaching face, a support for a sole having thermoplastic cement on its attaching

face located in side by side relation to said shoe supporting means, heating means adapted to activate the cement on both the shoe and the sole, means for pressing the shoe and the sole together, and a common movable support for the heating means and the pressing means adapted to locate said heating means and pressing means alternately in register with said shoe supporting means.

10 5. A cement sole attaching machine comprising means for supporting a shoe and a sole laid thereon in pressure sustaining position, pressure applying means movable with relation to the supported shoe and sole to apply pressure thereto, a support for said pressure applying means, means for adjusting said support heightwise of the machine, single means for both moving the pressure applying means into pressure applying position and locking it in that position, and yielding means for permitting continued movement of said single means after the pressure applying means is in pressure applying position.

15 10. A cement sole attaching machine comprising means for supporting a shoe and a sole laid thereon in pressure sustaining position, pressure applying means movable with relation to the supported shoe and sole to apply pressure thereto, a support for said pressure applying means, means for adjusting said support heightwise of the machine, a toggle for moving the pressure applying means into pressure applying position, means for straightening the toggle to operate and lock the pressure applying means, and yielding means for permitting the straightening of the 20 toggle after the pressure applying means is in pressure applying position, said toggle straightening means being operable in a reverse direction to break the toggle and unlock the pressure applying means.

25 11. A cement sole attaching machine comprising means for supporting a shoe and a sole laid thereon in pressure sustaining position, pressure applying means movable with relation to the supported shoe and sole to apply pressure thereto, a single means for moving the pressure applying means into pressure applying position, for locking it in that position and for unlocking it, and spring means for automatically moving the pressure applying means out of pressure applying position 30 after it has been unlocked.

CUTLER D. KNOWLTON.
